UNITED STATES PATENT OFFICE.

MARIETTA L. VAN DE VERG, OF HOBOKEN, NEW JERSEY.

DESIGN FOR A DRY-CEREAL DISH.

43,656.

Specification for Design.

Patented Feb. 25, 1913.

Application filed December 4, 1912. Serial No. 734,993. Term of patent 3½ years.

To all whom it may concern:

Be it known that I, MARIETTA L. VAN DE VERG, a citizen of the United States, residing at Hoboken, in the county of Hudson and State of New Jersey, have invented a new, original, and ornamental Design for Dry-Cereal Dishes, of which the following is a specification, reference being had to the accompanying drawing, forming a part thereof.

The figure is a perspective view of a dry cereal dish having my new design.

I claim:

The ornamental design for a dry cereal dish, as shown.

MARIETTA L. VAN DE VERG.
